UNITED STATES PATENT OFFICE.

ALONZO. C. RICKY, OF BOONE, IOWA, AND EDWIN D. MYERS, OF WOOSTER, OHIO.

HARNESS-SADDLE.

SPECIFICATION forming part of Letters Patent No. 292,360, dated January 22, 1884.

Application filed April 30, 1883. (No model.)

To all whom it may concern:

Be it known that we, ALONZO C. RICKY and EDWIN D. MYERS, citizens of the United States, residing at Boone, Boone county, Iowa, and Wooster, Wayne county, Ohio, have invented new and useful Improvements in Harness-Saddles, of which the following is a specification.

Our invention relates to certain new and useful improvements in the construction of harness-saddles. It has for its object to render the saddle automatically adjustable to the backs of differently-shaped horses; and with this end in view our invention consists in the peculiarities of construction and arrangement hereinafter described and specifically claimed.

In order that those skilled in the art to which our invention appertains may know how to make and use our improved saddle, we will proceed to describe its construction and operation, referring by letters to the accompanying drawings, in which—

Figure 1 is a rear elevation of a saddle embodying our invention; Fig. 2, a central longitudinal section, showing the saddle in a different adjustment from that shown at Fig. 1. Fig. 3 is a top or plan view of the same. Fig. 4 is a plan view of the yoke removed. Fig. 5 is a perspective view of the top plate, and Fig. 6 is a cross-section taken at x x of Fig. 2, showing the skirt-leather secured in place. The last three figures are made on an enlarged scale.

Similar letters indicate like parts in the several figures.

By the employment of our improved mode of construction and arrangement of parts, we are enabled to secure the several parts together with great celerity, and assist in relieving the skirts from the usual strain and wear at the point where the securing-screw passes through the same, and as will be readily understood by reference to the drawings and the description to follow hereinafter. The several parts being separably made and assembled renders it possible, in the event of breakage or wear of any one of said parts, to remove such part or parts and substitute therefor a duplicate.

50 A represents a yoke, which is cast in one

piece, and to which is attached, either in the process of casting or by any other known way, a check-hook, B. This yoke is formed with the ordinary back-strap loop, C. Each end of the yoke is formed with an eye, a, and cross-bar b, the latter adapted to rest in a concave or depression, c, cast in the upper end of the bottom plate, D, which is also formed at each end of said depression with upwardly-projecting lugs d, which serve to prevent any sidewise motion of the yoke A. The edges of the plate D extend upwardly to give a neat finish to the same, and to form a recess for the reception of the skirt-leathers E; and the upper end, above the depression c, is cast with an open slot, e, Fig. 6, adapted to receive the tongue f of the top plate, F, which tongue f is so shaped as to confine the cross-bar b of the yoke within the depression c, to form a hinge-joint. The lower portion of the bottom plate is adapted to receive the upper end of the skirt-leather E, which is confined between the top and bottom plates, F D, by a single screw, G, which draws said plates into parallelism and produces a clamp on the skirt-leather, so as to serve as an auxiliary to the screw G. In order that the plates F D may be brought into the position described, the tongue on the former is bent, as shown, and the latter is correspondingly raised for a short distance above the slot e, as clearly shown at Fig. 2. The plate D is secured to the pad by a short screw, g, at the upper end, and a nut within the pad. The screw G is secured in a similar manner, as clearly shown in the drawings.

H H are the terrets, which are secured in place below the ends of the yoke by screw-threads and nuts, in the usual way, and serve as additional means of securing the top and bottom plates, F D, in proper relation to each other. The housing I is secured in place in the usual way, as clearly shown.

What we claim as new, and desire to secure by Letters Patent, is—

1. The yoke A, formed at its ends with eyes a and cross-bars b, in combination with the bottom plate, D, having a recess for the reception of the cross-bar b and upwardly-projecting lugs d, and the top plate, F, provided

with the locking-tongue *f*, and adapted to be secured in place, substantially as and for the purpose set forth.

2. The bottom plates, *D*, provided at their upper ends with recesses *e* and lugs *d*, whereby the yoke may be held in place and secured against lateral or sidewise motion, substantially as hereinbefore set forth.

In testimony whereof we have hereunto set our hands in the presence of two subscribing to witnesses.

ALONZO C. RICKY.
EDWIN D. MYERS.
